PLYWOOD CHAIR STRUCTURE

Cloyd T. Konkle, Montoursville, Pa.

Application February 26, 1953, Serial No. 339,030

1. Claim. (Cl. 155—193)

1

This invention consists in new and useful improvements in a chair structure and while it relates to chairs in general, it is more particularly concerned with chairs of the type used in schools, public buildings and similar institutions.

Chairs of this type are subjected to extremely hard usage and because they are frequently moved from place to place it is important that their structures combine lightness and portability with a maximum of strength and rigidity. It is therefore the primary object of my invention to provide such a chair structure with simplicity in design and attractive appearance, yet which will withstand prolonged hard use.

Another object of the invention is to provide a chair so designed that the various elements thereof can be manufactured and assembled with a minimum of operations. To this end, in accordance with my invention, the forward legs and side seat supports of the chair are integrally formed and these elements, as well as the transverse, rear seat support, are preferably composed of suitable plywood strips which are cut and molded to the desired shapes.

The conventional type of chair used in public schools and the like is either of mortise and tenon type construction or dowel construction and in some instances a combination of both. These types of fabrication are dependent upon glue to secure the joints which, as a result of hard usage, frequently crystallizes in a comparatively short time causing the joints to become loose and pull apart.

It is therefore a further object of my invention to provide a chair construction wherein mortise and tenon joints as well as dowel joints are completely eliminated, thus avoiding the objectionable features characteristic to these types of construction.

A still further object of the invention is to provide a chair which is substantially made up of two groups of elements, respectively, pre-molded with common radii of curvature, at predetermined points so as to minimize manufacturing operations. One group comprises the front legs and integral side seat supports and the transverse seat support, while the other group comprises the seat proper and back rest.

With the above and other objects in view which will appear as the description proceeds, my invention consists in the novel features herein set forth, illustrated in the accompanying drawings and more particularly pointed out in the appended claim.

Referring to the drawings in which numerals of

2

like character designate similar parts throughout the several views,

Fig. 1 is a perspective view of a chair constructed and assembled in accordance with my invention;

Fig. 2 is a rear view of the chair; and

Fig. 3 is a collective view showing premolded plywood sheets from which the respective groups of parts may be formed.

As best seen in Fig. 1 of the drawings, my improved chair includes the usual basic elements consisting of front legs 5 and 6, rear legs 7 and 8 which are extended vertically to support a back rest 9 and finally the seat proper 10. The novelty in the chair resides primarily in the particular formation of the front legs 5 and 6 and their relationship to the remainder of the chair structure.

Each of these front legs 5 and 6 is preferably formed of plywood strips which are bent rearwardly at their upper ends to form substantially right angularly disposed seat supports 5a—6a. The rear extremity of each of these seat supports is again bent downwardly at a suitable angle to engage the forward faces of the rear legs 7 and 8 respectively, in the form of connecting lugs 5b and 6b.

A transverse brace or support 11 which underlies the seat 10, is also formed of a plywood strip, bent downwardly at an angle at each end to form connecting lugs 12, adapted to be secured to the opposed inner faces of the rear legs 7 and 8. Thus, the strip 11 serves the dual purpose of a transverse brace for the rear legs as well as a support for the rear portion of the seat 10.

The connecting lugs 5b and 6b are secured to the forward faces of the rear legs 7 and 8 by means of rivets or screws 13, while the connecting lugs 12 at the ends of the transverse support 11, are similarly secured to the opposed faces of the legs 7 and 8, by rivets or screws 14. The seat 10 rests upon the upper surfaces of the supports 5a, 6a and 11, to which it is respectively secured by rivets or screws 15 and 16. Thus, transverse support between the front legs 5 and 6 and their respective extensions 5a and 6a, is afforded by the seat itself.

The back rest 9 is secured to the forward faces of the rear legs 7 and 8 by means of rivets or screws 17, completing the assembly of the chair.

The main feature of my improved chair which facilitates the simplicity of construction and assembly and adds to its attractive and graceful appearance, resides in the design of multiple parts having common radii at curvature. As will

be seen in the drawings, the curvature at X, forming the juncture of the front legs, per se, and the rearwardly directed seat supports, as well as the curvature Y at the juncture of the seat supports and the rear leg connecting lugs, are of a common radius. This is also true of the curvatures Z at the junctures of the transverse seat support and its depending connecting lugs 12. It will be apparent that all of these elements can be formed either individually or simultaneously on the same wood bending or forming equipment.

The same is true with respect to the back rest 9 and the seat 10 which, as will be seen from Fig. 1, are provided with the same curvature and can be cut from the same sheet of plywood after it has been properly formed.

Although I do not intend to confine the invention in this respect, it will be observed from Fig. 3 that the front legs 5, 6 and integral seat supports 5a, 6a, as well as the transverse seat support 11, can be cut from one sheet of premolded or curved plywood and that the backrest 9 and seat 10 can be similarly produced from a single sheet of preformed plywood.

It will be apparent from the foregoing that this design not only affords simplicity in structure without sacrificing rigidity and durability, but facilitates mass production. Furthermore, it greatly enhances the neat and attractive appearance of the chair, especially for the type of use for which it is designed.

From the foregoing it is believed that my invention may be readily understood by those skilled in the art without further description, it being borne in mind that numerous changes may be made in the details of structure without departing from the spirit of the invention as set forth in the following claim.

I claim:

A chair constructed from three groups of plywood components; one of said groups comprising a pair of identical rear legs having vertically extended back rest supports integral therewith; a

second group, the components of which have been fabricated on a common form, and comprising a pair of front legs, the upper ends of which are directed rearwardly at substantially right angles to form integral seat supports, the rearward extremities of said seat supports being directed downwardly at substantially right angles to form relatively short integral connecting lugs, and a transverse brace member having its extremities bent downwardly at substantially right angles to form brace connecting lugs, the seat supports and the junctures connecting them respectively to their lugs and legs, and the transverse brace and the junctures connecting it to the brace lugs, being of common size and contour; and a third group, the components of which have been fabricated on a separate common form, and comprising a seat member and a separate back rest, curved transversely about a common radius; said seat support connecting lugs being adapted to abut the adjacent faces of respective rear legs, means connecting the lugs to said legs, said transverse brace being interposed between said rear legs with its connecting lugs abutting respective legs, means for connecting said last named lugs to said legs, said seat member resting on and secured to said seat supports and brace, and said back rest being secured to said back rest supports.
